FIG. 5.

UNITED STATES PATENT OFFICE

2,678,590

DEVICE FOR SETTING-UP COLLAPSIBLE
CARDBOARD CARTONSJoseph K. Eaton, Newark, N. Y., assignor to
Bloomer Bros. Company, Newark, N. Y., a cor-
poration of New York

Application November 25, 1949, Serial No. 129,332

3 Claims. (CL. 93—53)

1

This invention relates to devices for setting up or erecting cardboard cartons of the folding variety adapted to be collapsed into flat condition for transportation and storage, such, for example, as disclosed in United States Letters Patents Nos. 2,277,327 (Fig. 8) and 2,333,181 (Figs. 3 and 7). In situations where such cartons are employed in substantial quantities, the setting up or erection thereof, for filling with the contents, becomes, if accomplished manually, a time-consuming and somewhat burdensome operation, and mechanisms are known for automatically unfolding and distending or setting up the cartons for receiving their contents.

In a copending application for Letters Patent, Serial No. 95,488, filed May 26, 1949, Machine for Setting Up Cartons, there is disclosed a mechanism in which the collapsed cartons are moved continuously along a path and erected, at least in large part, by stationary devices arranged to separate, unfold and erect the carton portions during movement thereof along the guideways, and the present invention provides a device for use in such a machine.

The object of the present invention, therefore, is to provide an improved device for use in such a machine for efficiently engaging between carton portions collapsed into substantial contact with each other and to progressively separate and unfold such portions to erect the carton during the movement thereof along the guideways provided therefor.

To these and other ends the invention resides in certain improvements and combinations of parts, all as will be hereinafter more fully described, the novel features being pointed out in the claims at the end of the specification.

In the drawings:

Fig. 1 is a top plan view of a portion of a carton erecting machine having applied thereto a device embodying the present invention;

Fig. 2 is a side elevation thereof;

Fig. 3 is a sectional elevation on the line 3—3 in Fig. 2;

Fig. 4 is a sectional elevation on the line 4—4 in Fig. 2;

Fig. 5 is a sectional elevation on the line 5—5 in Fig. 2, and

Fig. 6 is an exploded perspective view of parts of the device detached.

2

The preferred embodiment of the invention is herein disclosed as adapted for use in the setting up of a carton such as disclosed in the said patents and in a machine such as disclosed in said copending application. Such a carton is shown in Fig. 3 in flat collapsed condition and in Figs. 4 and 5 as progressively unfolded or distended in the course of setting it up in erected condition ready for filling with its contents. The carton comprises a longitudinal cell-forming partition 10 projecting along one side edge and a pair of upper and lower folded portions, 11 and 12, which form, when erected, the front and rear side walls and the V-shaped bottom wall of the carton. In collapsed condition, these folded portions 11 and 12 are superposed in engagement with each other, as shown in Fig. 3, and so as to require separation and progressive movement apart from one another, as shown in Figs. 4 and 5, in order to accomplish the erection of the carton.

The machine disclosed in said copending application comprises a hopper (not shown) for receiving a stack of the collapsed cartons and means for feeding the cartons longitudinally, one at a time, for cooperation with the devices for erecting each carton during such movement. Such means comprises spaced grooved guideways or rails, 13 and 14, the former for guiding the edge of the longitudinal partition 10 and the latter for guiding the superposed folded portions 11 and 12. The carton is moved continuously along such guideways by means comprising an endless chain 15 supported in the machine and moved by motor means (not shown). Projecting upwardly at spaced points along the chain are a series of arms 16, the upper ends of which are arranged to engage the ends of the collapsed cartons and push them, one after another, along the guideways 13 and 14, as indicated in Fig. 3, the foregoing elements being all parts of the machine described and claimed in said copending application.

The present invention resides in a device positioned beyond the end of the guideway 14 (Fig. 1) for entering between and initially separating the superposed carton portions 11 and 12 and then progressively distending or moving them apart to set up the carton. Such device comprises, preferably, an upwardly extending bracket 17 (Fig. 4) fixed on the frame of the

machine and carrying at its upper end a screw or bolt 17a which passes through central openings in and supports a thin-edged separating element 18 preferably in the form of a plate or disk, as shown, and upper and lower guide members or plates, 19 and 20, located on opposite sides of element 18, for properly guiding and positioning the carton portions for separation thereof by the element 18, as herein more fully described.

The separating plate 18 is preferably of arcuate or circular and substantial disk-shape interrupted by an inwardly extending notch 21, as shown (Fig. 6). The curved or arcuate periphery of the element 18 is beveled to produce a thin, substantially knife-like edge 22 for entry between the contacting portions 11 and 12 of the carton.

The carton portions are accurately positioned for the separating action of element 18 by the guide plates 19 and 20. These plates are preferably of arcuate or disk-like shape, cut away at 23 and 24, respectively, for a purpose hereafter described. The curved peripheries of these members or plates are each formed with inwardly inclined surfaces, 25 and 26, respectively, for engaging the outer surfaces of the carton portions 11 and 12 and for accurately positioning the plane of engagement between them in line with the knife edge of element 18 as shown in Fig. 2, as the carton is moved along its guideways by the continuously moving arms 16. The element 18 and members 19 and 20 are clamped stationarily on bracket 17 by the screw 17a. It is apparent from the above description that the carton portions are precisely positioned by the beveled edges of the members 19 and 20 and engage at their corners, first with the curved sharp edge of element 18 by which they are reliably separated and moved apart by the increasing thickness of the beveled edge of the element, and its increasing penetration into the carton path, so as to be moved from the position shown in Fig. 3 to that shown in Fig. 4.

As the corners of the carton portions, initially separated as described above, pass beyond the point of maximum penetration of the element 18, they engage with the tapered end 27 of a shoe, indicated generally at 28, for continuing the separation of the carton portions. The shoe end 27 is a plate having an edge 27a which is beveled and inclined further inwardly, as shown in Figs. 1 and 2, for progressively increasing the distension of the carton portions as they move along the guide. Shoe end 27 is carried by a bracket 29 fixed on the frame of the machine. Beyond the leading end 27 of the shoe, the carton portions engage the main body of the shoe 28, the edge of which is inclined inwardly as at 30 to progressively penetrate further between the carton folds. As shown in Fig. 1, the guideway 13 is inclined and progressively approaches the shoe, so that the latter is caused to increasingly press inwardly between carton portions 11 and 12. Shoe 28 has opposite side surfaces, 31 and 32, which are flared outwardly away from each other to progressively increase the separation of the carton portions as shown in Fig. 5.

At the end of shoe 28 the separated carton portions engage with a series of wedge-shaped rollers, one of which is shown at 33 (Figs. 1 and 2), which further increase the separation of the carton portions with a minimum of friction, for completing the erection of the carton, as more fully described in said copending application.

It is apparent from the above description that the invention provides a precision device for accurately and reliably engaging between the contacting surfaces of the bottom portions of the carton and initially spreading them apart for proper engagement with the inclined surfaces of shoe 28 and eventually with the wedge-shaped roller 33, so as to reliably and progressively spread apart the side and bottom wall portions of the carton to erect the same in cooperation with the mechanism disclosed in the said copending application. The invention thus provides a simple and efficient device for insuring alignment between the device and the contacting surfaces of the carton portions and for engagement therebetween and progressive separation thereof, as required for erecting the carton, this function being accomplished, moreover, by relatively simple, stationary parts requiring only the continuous movement of the cartons along their guideways.

It will thus be seen that the invention accomplishes its objects and while it has been herein disclosed by reference to the details of a preferred embodiment, it is understood that such disclosure is intended in an illustrative, rather than a limiting sense, as it is contemplated that various modifications in the construction and arrangement of the parts will readily occur to those skilled in the art, within the spirit of the invention and the scope of the appended claims.

I claim:

1. A device for erecting collapsible cardboard cartons having portions thereof collapsed into substantial engagement with each other, said device comprising guideways for the collapsed carton, means for moving the carton along said guideways, a pair of spaced stationary members having inner peripheral surfaces thereof inclined inwardly and toward each other for engaging the outer sides of said carton portions to accurately center the same therebetween during said carton movement, an element formed with a thin edge arranged to enter between and initially separate said carton portions while positioned by said members, and means for entering between said separated portions and for progressively increasing the separation thereof, for erecting said carton during movement thereof along said guideways.

2. A device for erecting collapsible cardboard cartons having portions thereof collapsed into substantial engagement with each other, said device comprising guideways for the collapsed carton, means for continuously moving the carton along said guideways, a pair of spaced stationary members having inner peripheral surfaces thereof inclined inwardly and toward each other for engaging the outer sides of said carton portions to accurately center the same therebetween during said carton movement, a stationary plate having a thin edge of curved shape arranged to enter between and initially separate said carton portions while positioned by said members, and means for entering between said separated portions and for progressively increasing the separation thereof, for erecting said carton during movement thereof along said guideways.

3. A device for erecting collapsible cardboard cartons having portions thereof collapsed into substantial engagement with each other, said device comprising guideways for the collapsed carton, means for moving the carton along said guideways, a pair of spaced members having inner peripheral surfaces thereof inclined inwardly

and toward each other for engaging the outer sides of said carton portions to accurately center the same therebetween during said carton movement, a stationary plate having a curved peripheral portion beveled to a thin edge arranged to progressively enter between and initially separate said carton portions while positioned by said members, a stationary shoe having longitudinally flared sides for entering between said separated portions and for progressively increasing the 10 separation thereof, and wedge-shaped roller means arranged to engage between and further

increase the separation of said carton portions, for erecting said carton during movement thereof along said guideways.
